[57] CLAIM

The ornamental design for an combined integrally formed tank sump and lid, as shown and described.

DESCRIPTION

FIG. 1 is a perspective view of a combined integrally formed tank sump and lid showing our new design;

FIG. 2 is a top plan view thereof;

FIG. 3 is a front elevational view thereof, which is identical to the rear elevational view;

FIG. 4 is a bottom plan view thereof; and,

FIG. 5 is a left-side elevational view thereof, which is identical to the right-side elevational view.
